UNITED STATES PATENT OFFICE.

JESSE M. PAYNE, OF SOMMERSVILLE, ALABAMA, ASSIGNOR TO PERFECTION DYEING MACHINE CO., OF COLUMBUS, GEORGIA, A CORPORATION OF GEORGIA.

DYEING-MACHINE.

1,088,617.

Specification of Letters Patent.

Patented Feb. 24, 1914.

Application filed May 15, 1913. Serial No. 767,931.

To all whom it may concern:

Be it known that I, JESSE M. PAYNE, a citizen of the United States, residing at Sommerville, in the county of Lee and State 5 of Alabama, have invented certain new and useful Improvements in Dyeing-Machines; and I do hereby declare the following to be a full, clear, and exact description of the invention, such as will enable others skilled in 10 the art to which it appertains to make and use the same.

My present invention relates to improvements in dyeing apparatus of the general type of the patents granted to the Perfection 15 Dyeing Machine Company, and illustrated in patents to Jesse M. Payne and George G. Wallace #887,511, granted May 12, 1908 for improvements in dyeing machines; also to Payne and Wallace #1,053,063 granted February 11, 1913; and to Payne and Wallace 20 #1,057,265 granted March 25, 1913, and the present invention is intended to provide improvements upon the apparatus illustrated and described in said patents.

The invention is especially intended to 25 provide a warper beam composed of a series of spiders mounted upon a central shaft; certain of the spiders carrying a series of fixed slats, and the other spiders being adapt- 30 ed to wedge outward a series of movable slats, so that the yarn may be wound upon the movable slats when in the extensible position, and then the warper beam may be 35 immersed in the vat. When the dyeing process is partly completed, the extended slats are permitted to move inward under 40 the shrinking action of the yarn, causing the yarn previously supported by the extensible slats to be supported on the fixed slats whereby more perfect access of the dye 45 liquor to the inner layers of the yarn is secured, and whereby any streaky effect, due to continuous contact of the yarn with the slats, incident to the dyeing, washing, or other treatment of the yarn, is avoided.

My invention will be understood by reference to the accompanying drawings, in which the same parts are indicated by the same symbols of reference throughout the 50 several views.

Figure 1 shows a central vertical section through the warper beam, parts being shown in elevation; Fig. 2 shows a section along the line 2-2 of Fig. 1 and looking in the 55 direction of the arrows; Fig. 3 shows a sec-

tion along the line 3-3 of Fig. 1 and looking in the direction of the arrows; Fig. 4 is a detail showing one of the extensible slats removed from the apparatus; and Fig. 5 shows the cam engagement of the extensible slat and the slidable spider for forcing the slats outward and permitting the slats to move inward toward the axis of the warper beam.

The warper beam is mounted upon a suitable shaft 1, which, when in the dye vat, is rotated in any convenient way, as by means of the worm wheel 2, the worm 3 and the pulley 4; the said worm and pulley being shown in dotted lines. The warper beam is 60 provided with two heads 5 and 5^a. One of these heads is perforated as at 6 to permit the passage of the dye liquor to the center of the beam, as fully described in the patents aforesaid. The special arrangements for rotating the warper beam and for controlling the flow of the dye liquor, or the washing fluid, backward or forward, are fully described in the patents aforesaid, and not being a part of my present invention, will not 65 be further discussed herein.

Mounted on the shaft 1 are a series of fixed spiders 7 to the periphery of which are secured the fixed slats 8, which are preferably of metal and are rigidly attached to 70 the spiders 7, but wooden slats may be used if desired. These fixed spiders form with the fixed slats and the fixed heads of the warper beam a spool-shaped skeleton frame, 75 entirely distinct from the sliding frame carrying the collapsible slats which will now 80 be described.

Slidably mounted on the shaft 1 are a series of spiders 9 and 9^a which are connected together by means of the rods 10 and 95 are spaced apart by means of the thimbles or spacing sleeves 11; thus these various spiders 9 and 9^a form with the connecting rods and thimbles a frame which slides as a unit on the shaft 1. This sliding motion 100 is imparted by the screw-threads 12 on the adjusting screws 13, which screw-threads 12 engage corresponding threads 12^a in the spider 9. The outer ends of these screws 13 are squared as at 14 and the two screws 105 are connected together as by means of the pinions 15 mounted upon the respective screws, and the gear wheel 16 mounted on the shaft 1. By this arrangement, if either screw be turned, as by a hand wrench, both 110

screws will be turned, and a sliding movement will be given to all of the spiders 9 and 9^a. By having two screws on opposite sides of the shaft 1, any tendency to bind is avoided, as would be the case were a single screw only used to slide the various spiders referred to.

Any suitable device for keeping the various gear wheels in engagement may be adopted. There are many well known in the art.

The travel of the spider 9 and of the other spiders sliding therewith is limited, in reverse directions, by the nuts 18 and 19. As shown in Fig. 1, the spider 9 is moved to the farthest position to the right causing the movable slats 20 to be extended to the position shown in Fig. 2; while when the spider 9 is moved to the other limit of travel engaging the nuts 19, the extensible slats 20 would be in their withdrawn position shown in Fig. 3. The outward movement of these slats radially with regard to the axis 1 is effected by the co-action of cam faces 21, on the spiders 9 and 9^a, and wedges 22 secured on the inner side of the slats, as shown most clearly in Figs. 4 and 5. The various spiders are provided with radial slots adapted to permit the radial movement of the extensible slats 20 therein, as shown most clearly in Figs. 2 and 3. It will thus be seen that by moving the spider 9 to the right, as shown in Fig. 1, the extensible slats will be forced outward to the position shown in Fig. 2, while if the wet yarn be wound on the warper beam, and the spider 9 be moved in the reverse direction, the extensible slats will be forced inward by the contraction of the yarn until the yarn will rest on the fixed slats 8, where it will remain until removed from the warper beam, in the ordinary process of unwinding.

It will be obvious that the extensible slats may be forced out again while the yarn is wound thereon, but in practice this will ordinarily be unnecessary.

The operation of the device is as follows:—The wooden slats 20 are first fully expanded to the position shown in Fig. 2 and the yarn is wound on the warper beam. When the beam is filled and before being placed in the dye vat, the wooden slats are contracted slightly, say for a quarter of an inch, leaving a small space, say quarter of an inch, between the yarn and fixed slats. Then the dyeing is carried on for a while after which the wooden slats are again contracted full distance bringing the yarn in contact with the fixed slats and leaving a space between the fixed slats and the wooden slats below, of say a quarter of an inch. In this way, the inevitable contraction of the yarn is provided for and the changes in the position of the movable slats are such that the streaky effect known as "slat marks" is

prevented, and at the same time the yarn is finally left in contact with the fixed slats, giving a firm true and level support to the yarn across the entire beam; this largely avoids any irregularity in tension or winding of the yarn and enables the yarn to wind off on the slasher uniformly and without slack ends or other similar troubles. Where all of the slats are made collapsible, as described in the previous patents hereinbefore referred to, there is a tendency for the slats to be more or less unstable causing slight irregularities in winding the yarn on and off the beam.

It will be noted that the fixed slats are arranged at the same distance apart peripherally and the movable slats project up between the fixed slats so that there is a symmetrical support for the yarn when the movable slats are withdrawn. Another advantage of the beam is that the fixed slats are made preferably of metal and form a part of the rigid framework of the apparatus, while the movable slats being larger and ordinarily made of wood, are more liable to injury, and when the beam is being handled or transported from place to place, these wooden slats would be in the withdrawn position and protected from being broken or bruised while the beam is emptied. Thus, with the herein described apparatus, I combine all the advantages of the beam having rigid framework and fixed slats to the advantages of extensible slats to prevent the streaky effect occasioned when the yarn is in contact with the face of the slats during the entire operation of dyeing.

It will be obvious that various modifications might be made in the herein described apparatus and in the construction, combination and arrangement of parts which could be used without departing from the spirit of my invention.

Having thus described my invention, what I claim and desire to secure by Letters Patent of the United States is.

1. The combination in a warper beam of a plurality of fixed slats forming the periphery of said warper beam, and intermediate slats mounted to move radially away from the axis thereof, with means for reciprocating said intermediate slats outwardly away from the axis of said warper beam, to form a skeleton cylinder of greater diameter than that of said fixed slats, and for withdrawing all of said movable slats wholly within the periphery of the said cylinder formed by said fixed slats, said means comprising a series of spiders provided with cam faces, and wedges secured to said movable slats engaging said cam faces, with means for sliding said spiders longitudinally on the axis of the warper beam, substantially as described.

2. The combination in a hollow warper

- beam of a central shaft therefor, a plurality of fixed slats normally forming the periphery of said warper beam, spiders fixed on said shaft and forming fixed supports for 5 said fixed slats, intermediate slats mounted to move radially away from the axis thereof, and means for simultaneously moving the movable slats away from or toward the axis of said warper beam, said means comprising 10 a series of spiders slidably mounted on said shaft, and having cam faces arranged near their peripheries, wedges projecting inwardly from said slats, and means for simultaneously sliding said spiders when desired, 15 substantially as described.
3. The combination in a hollow warper beam of a central shaft therefor, a plurality of fixed slats normally forming the periphery of said warper beam, spiders fixed 20 on said shaft and forming fixed supports for said fixed slats, intermediate slats mounted to move radially away from the axis thereof, and means for simultaneously moving the movable slats away from or toward 25 the axis of said warper beam, to form a skeleton cylinder of greater diameter than that of said fixed slats, and for withdrawing all of said movable slats wholly within the periphery of the said cylinder formed by 30 said fixed slats, said means comprising a series of spiders slidably mounted on said shaft, and having cam faces arranged near

their peripheries, wedges projecting inwardly from said slats, and means for simultaneously sliding said spiders when desired, substantially as described.

4. The combination in a warper beam of a plurality of fixed slats forming the periphery of said warper beam, and intermediate slats mounted to move radially away 40 from the axis thereof, with means for reciprocating said intermediate slats outwardly away from the axis of said warper beam, to form a skeleton cylinder of greater diameter than that of said fixed slats, and for 45 withdrawing all of said movable slats wholly within the periphery of the said cylinder formed by said fixed slats, said means comprising a series of spiders provided with cam faces, and wedges secured to said movable slats engaging said cam faces, with 50 means for sliding said spiders longitudinally on the axis of the warper beam, comprising a pair of screws engaging one of said spiders, a pinion in each of said screws, and a gear wheel mounted between and engaging both of said pinions, substantially as described.

In testimony whereof, I affix my signature, in presence of two witnesses.

JESSE M. PAYNE.
